(57) **CLAIM**

The ornamental design for a control station for a motorized vehicle operable to transport material, as shown and described.

DESCRIPTION

FIG. 1 is a perspective view of a control station for a motorized vehicle operable to transport material, in accordance with the claimed design;

FIG. 2 is another perspective view thereof;

FIG. 3 is a rear elevation view thereof;

FIG. 4 is a front elevation view thereof;

FIG. 5 is a left side elevation view thereof;

FIG. 6 is a right side elevation view thereof;

FIG. 7 is a top plan view thereof.

FIG. 8 is a bottom plan view thereof; and,

FIG. 9 is a perspective view of the control station shown in FIG. 1 and illustrating an example environment in which the control station may be used, whereby the control station is included in a motorized vehicle operable to transport material.

The broken lines showing portions of the control station for a motorized vehicle operable to transport material and environment forms no part of the claimed design.
